FIREPLACE DOME

Filed Feb. 4, 1929

WITNESS

J. J. Mains

H. H. Walters INVENTOR.
BY *Denison & Thompson* ATTORNEY.

UNITED STATES PATENT OFFICE

HERBERT H. WALTERS, OF SYRACUSE, NEW YORK, ASSIGNOR TO CHEMICAL TOILET CORPORATION, OF SYRACUSE, NEW YORK, A CORPORATION OF NEW YORK

FIREPLACE DOME

Application filed February 4, 1929. Serial No. 337,373.

This invention relates to a fire-place dome, preferably of boiler iron or other suitable sheet metal adapted to be installed in the upper portion of the fire-place to serve as a flue connection between the fire-place and chimney in a manner somewhat similar to the dome of the sheet metal fire-place shown in my pending application, Serial Number 279,392 filed May 21, 1928.

10 The main object is to provide a dome of this character as a unitary article of manufacture to be installed in the usual brick or other fire-place construction to serve the triple purpose of a flue section, a draft regulator and a 15 down-draft deflector.

Another object is to permit the damper of the draft regulator to be easily and quickly removed or replaced through the draft opening in the bottom part of the dome.

20 A further object is to permit the dome to be used as a form against which the bricks or other masonry may be laid to assure the proper deflection of the products of combustion from the fire-place to the chimney and at the 25 same time to reduce the liability of leakage of the gas, smoke and other products in transit from the fire-place to the chimney flue.

Other objects and uses relating to specific 30 parts will be brought out in the following description.

In the drawings:—Figure 1 is a front face view of a portion of the brick fire-place partly broken away to show a part of one 35 side of the dome.

Figure 2 is a vertical sectional view taken in the plane of line 2—2, Figure 1.

Figure 3 is a perspective view of the detached dome, a portion of which is broken 40 away to show the adjacent end of the damper seat, the damper being removed.

In order that the invention may be clearly understood I have shown a portion of a brick fire-place 1, of any conventional construction connected by an opening 2 to the chimney flue 3, in which is placed an upwardly tapered dome 4 of boiler iron or other suitable sheet metal.

It is of course preferable to install this 50 dome during the initial construction of the

fire-place and chimney, but obviously it may be installed in previously built fire-places and when thus installed forms a flue connection between the fire-place proper and the flue in the chimney, as shown in Figure 2. 55

The chimney flue 3 is usually rectangular in cross section and of considerably less area than the horizontal area of the fire place opening and is also preferably located some distance to the rear of the vertical center 60 of the fire-place and approximately midway between the opposite sides thereof and, for this reason, the upper end of the hood 4 is of correspondingly less area than its base, so that its front wall and its opposite side walls 65 are inclined upwardly toward the apex of the dome while the rear side may be disposed in a substantially vertical plane as shown in Figure 2.

The opening as 4' in the apex of the dome 70 4 is rectangular and corresponds approximately to the cross sectional area of the flue 3 with which it is registered.

The bottom wall 5 of the dome 4 is substantially flat and horizontal and extends 75 forwardly from the rear wall to the front wall except that its front portion adjacent to the front wall is provided with a draft opening 6 to permit the passage of the products of combustion from the fire-place into 80 the dome and thence out through the flue 3.

This opening or passage 6 is controlled by a damper 7, having its lower rear edge seated in the groove of a V-shaped member 8 which is secured to the upper face of the bottom 85 wall 5 just at the rear of the opening 6 with the upper side of the groove facing upwardly.

The damper 7 extends the full length of the opening 6 within the dome 4 and when seated in the grooved member 8 may be rocked 90 forwardly and rearwardly into and out of an engagement within the inner face of the front wall of the dome as shown in Figure 2.

That is, the damper is fulcrumed on the 95 member 8 and is of greater cross sectional width than the transverse width of the opening 6 so that when closed it will assume an upwardly and forwardly inclined position with its ends in close proximity to the end 100

walls of the dome thereby forming what may be termed a deflecting plate which cooperates with the rear portion of the bottom wall 5 to prevent down-draft from the smoke flues into the fire-place.

5 When the damper is opened, as shown by dotted lines in Figure 2, it also cooperates with the bottom wall 5 to deflect the products of combustion upwardly in case of down-draft through the flue thereby reducing to a minimum the liability of blowing the smoke and ashes from the fire-place into the room in which the latter is located.

10 For example when the damper is in its closed or open position it will always project upwardly more or less from the bottom wall 5 just at the rear of the opening 6, so that any down-draft through the flues will impinge against the bottom wall 5 and will 15 then be deflected upwardly by the damper 7 to pass out through the flue near the front side thereof while the down-draft may at the same time flow downwardly along the rear side of the flue.

20 25 The base of the dome is provided with an outwardly projecting marginal flange 5' along the lower edges of the opposite side walls and rear wall of the dome to be incorporated in the mason work of the fire-place for firmly 30 holding the dome in operative position.

35 The damper 7 is provided with an operating member 9, having its upper end riveted or otherwise rigidly secured at 10 to the front face of the intermediate portion of the damper and its remaining portion extended 40 downwardly through the opening 6 and into the fire place 1, the lower end of said member being provided with an eye 11 to which may be connected any suitable instrument for 45 rocking the damper about its fulcrum member 8.

50 45 The member 9 is provided with a lug 12, adapted to be engaged by a pawl 13 which is pivoted at 14 to the under side of the bottom wall 5 of the dome to extend forwardly from its pivot across the upper side of the lug 12, and has its lower edge serrated at 15 for interlocking engagement with said lug 12.

55 The forward end of the pawl 13 is weighted to automatically engage its serration 15 with the lug 12, to hold the damper in its adjusted position as the operating member 9, is moved forwardly and rearwardly.

60 55 The front, rear and side walls of the dome are rigidly secured to each other to form gas-tight joints and for the same purpose the lower edges of said walls are rigidly secured to the bottom plate 5 around the opening 6, so that the products of combustion escaping from the fire place will pass through the opening 6 and will enter the dome and pass into the chimney flue 3 without liability of escaping into the room in which the fire place is located.

65 55 This sheet metal dome may be manufac-

tured and sold at a comparatively low cost and during installation serves as a form against which the masonry may be constructed and when installed affords a smooth lining for the upper portion of the fire place to reduce the liability of the accumulation of soot and also to afford a more effective upward draft for the products of combustion.

70 75 Another advantage is that the same device may be used as a support for the damper which in its peculiar relation to the bottom 5 of the dome reduces to a minimum the liability of a down-draft from the flue into the fire-place.

80 85 It will also be noted that the particular manner of supporting the damper 7 upon the fulcrum bearing 8 permits said damper to be placed in an operative position and removed through the opening 6 by simply lifting it out of engagement with its member 8 and then tilting it endwise and transversely until it is free to pass through said opening.

85 What I claim is:

90 95 1. A sheet metal dome adapted to be installed as a connection between the upper portion of a fire-place and smoke flue of the chimney and comprising an upwardly tapered tubular shell having a horizontal bottom wall provided with a relatively narrow opening therethrough adjacent the front wall to allow the passage of the products of combustion from the fire-place to the interior of the shell, a V-shaped bearing member secured to the bottom wall adjacent the rear wall of the opening with its open side uppermost, and a damper loosely fulcrumed in the open side of said member for rocking movement to and from a position across said opening and adapted to be removed from said member by upward displacement.

100 105 2. A sheet metal fireplace dome as in claim 1 in which the bottom plate and front wall of the shell form an acute angle with each other, and the damper, when closed, extends from the rear wall of said opening across said angle.

110 In witness whereof I have hereunto set my hand this 2nd day of February, 1929.

115 HERBERT H. WALTERS.
